AUTOMATIC VACUUM CLEANERS

Allen P. Cawl, Noroton Heights, Conn., assignor to Electrolux Corporation, Old Greenwich, Conn., a corporation of Delaware

Application February 29, 1956, Serial No. 568,458

7 Claims. (Cl. 200—67)

My invention relates to a vacuum cleaner and more particularly to a cleaner of the automatic type, that is one in which a predetermined increase in the pressure drop through the dust separating bag effects a control of the cleaner, such as opening the front cover or shutting off the motor, or both.

More particularly my invention is concerned with an improved electric switch for controlling the operation of the motor, both manually and in response to the aforesaid increase in pressure drop, together with means for mounting the switch on the vacuum cleaner.

Further objects and advantages of my invention will be apparent from the following description when considered in connection with the accompanying drawings which form part of the specification, and of which:

Fig. 1 is a longitudinal cross-sectional view of a vacuum cleaner embodying my invention;

Fig. 2 is a partial front view of the cleaner shown in Fig. 1 with the front cover removed, and on an enlarged scale;

Fig. 3 is a cross-sectional view taken on the line 3—3 of Fig. 2;

Fig. 4 is a cross-sectional view taken on the line 4—4 of Fig. 1;

Fig. 5 is a cross-sectional view on an enlarged scale of the electric switch shown in Fig. 1;

Fig. 6 is a cross-sectional view taken on the line 6—6 of Fig. 5; and

Fig. 7 is a cross-sectional view taken on the line 7—7 of Fig. 5.

Referring more particularly to Fig. 1, reference character 10 designates a hollow housing adapted to be supported in a substantially horizontal position on a horizontal surface by means of rear wheels 12 and a front caster wheel 14. Mounted within the housing 10 is a motor fan unit including an electric motor 16 and a fan 18 having an inlet opening 20. Secured to the otherwise open end of the housing 10 is an end cap 22 which supports an air filter 24. Cap 22 is formed with an exhaust opening 26 beyond the filter.

To the other end of the housing 10 is secured a ring 28 formed with an inwardly extending flange 30 to which is secured an inner perforated body 32. A disposable dust bag 34 is removably received within the inner body and includes a porous paper bag portion 36 secured to a cardboard disc 38. The disc is adapted to seat in airtight relation against a flexible gasket 40 carried by the front ring 28.

Pivoted to the front ring at 42 is a front cover or closure member 44 which carries an inlet tube 46 which extends through an aperture 48 formed in the cardboard disc 38. A resilient rubber ring 50 is carried by the conduit 46 and bears against the central portion of the cardboard disc so as to hold the disc against the gasket 40 and a plate member 51 for enclosing the hollow space within cover 44 is carried by the ring 50. The outer end of inlet conduit 46 is formed as a portion of a cou-

2

pling 52 adapted to removably connect it to the end of a suction hose.

Mounted in the space within front cover 44 below the inlet conduit 46 and designated generally by reference character 54 is a control diaphragm mechanism. This includes a casing forming a diaphragm chamber in which is disposed a flexible diaphragm 56. The space in the chamber to the right of the diaphragm, as viewed in Fig. 1, is connected through a tube 58 with an opening 46. A tube 60 is connected to the other side of the diaphragm chamber and extends around the inlet conduit 46 and terminates in an opening 62 formed near the side edge of the plate 51 of the front cover, as is shown in Fig. 4. When the front cover is in place, this opening 62 is aligned with the flared end 64 of a tube 66 which is carried by the front ring 28, as is shown in Figs. 2 and 3, and which extends into the space between the casing 10 and inner body 32.

20 The casing of control member 54 includes a cylindrical portion 68 within which is movably mounted a valve body consisting of a sleeve 70 to which is secured a knob 72 which has threaded engagement with the cylindrical part 68. Sleeve 70 is formed with an internal annular shoulder forming a valve seat with which cooperates a valve member 74, which is urged into sealing contact with the seat by means of a spring 76. The valve 74 is secured to a stem 78 which extends into the diaphragm chamber so as to be contacted by the diaphragm 56 as the latter is displaced to the left. The diaphragm is normally urged to the right by means of a loading spring 80. As will be seen clearly in Fig. 1, the knob 72 is accessible from the exterior of cover 44 for manual rotation and it will be seen that, because of its threaded engagement with portion 68, rotation of the knob moves the latter along with the sleeve 70 and the valve 74 axially of the cylindrical portion 68 so as to vary the displacement required of the diaphragm 56 before it strikes the stem 78. A tube 82 connects the interior of cylindrical portion 68 to the interior of a power diaphragm chamber 84.

The right-hand end, as viewed in Fig. 1, of chamber 84 is closed by means of a flexible diaphragm 86, the other side of which is exposed to atmospheric pressure. 45 This diaphragm carries a stem 88 which engages an arm 90 of a cover latch 92 which is pivoted to the front cover at 94. A spring 96 tends to pivot the latch in a counter-clockwise direction so as to engage it with a keeper 98 mounted on the front ring 28, as is shown in Figs. 1 and 2.

50 Mounted on the upper outer surface of casing 10 is a channel member 100 which extends from the front ring 28 longitudinally of the casing. The front end of a carrying handle 102 is secured against the upper surface of channel 100 and the channel is secured to the casing 10 by means of fastening means 104. Slidably mounted within the channel is a rod 106, the left-hand end of which extends through an opening formed in the front ring 28 and the rod is urged outwardly through this opening by means of a coil spring 108. 60 When the cover 44 is closed it strikes the end of rod 106 and displaces it to the right, as viewed in Fig. 1.

Mounted to the right of the handle 102 is an electric switch designated generally by reference character 110. The details of the switch are shown more particularly 65 in Figs. 5, 6 and 7. The switch includes a switch case 112 of insulating material having a portion 114 engaged by the rear end of the handle, a fastening member 116 extending through the handle and the portion 114 so as to secure both the handle and the switch case 112 to the casing 10. The case includes side walls 118 and a rear wall 120. Spaced inwardly from each of the side walls 118 is a seat 122 formed with a slot 124

therethrough. Mounted on the seat 122 is a toggle switch 126 having an actuating arm 128 which extends downwardly through the slot 124. The switch includes an electric terminal 130 which is securely fixed, as by the bolt 132 to an extension 134 formed on the inner end of a contact prong 136. This prong extends through a slot formed in the rear wall 120 of the switch case and is fixed in place therein by means of a pin 138 of insulating material which extends through a vertical bore in the rear wall and through an aligned opening of the prong 136. A second contact prong 140 extends in spaced relation to prong 136 through another slot in the rear wall 120 and is held in place by the lower portion of the pin 138. These prongs are adapted to engage the plug 139 of an electric cord 141, shown in Fig. 1.

A U-shaped member 142 is provided with outwardly extending semi-cylindrical pins 144 near the free ends of the legs, while the other ends are connected together by means of a cross member 146. U-shaped member 142 is made of flexible material so that in assembling the parts, the free ends of the legs may be squeezed together sufficiently to permit the extending pins 144 to pass through the space between side walls 118 and the seat 122 of the switch case until they snap into recesses in the top edges of the two side walls. The cross member 146 is formed with a recess 148 into which extends the lower end of the actuating arm 128 of the toggle switch. Consequently, pivoting of the U-shaped member about the pins 144 causes the actuating arm 128 to be pivoted so as to operate the switch mechanism.

A manually movable element 150 is formed with flanges 152 which engage the upper free ends of the legs of the U-shaped member, thus preventing the ends of the legs from being moved inwardly towards each other which would result in disengagement of the pins 144 from the recesses of the side walls 118. Element 150 is also provided with a pair of outwardly extending semi-circular pins 154 which mate with the semi-circular pins 144. The pins 154 are retained in the recesses formed in the side walls 118 by flanges 156 of an outertrim member 158 which surrounds the switch-case 112.

The cross member 146 is formed with an opening 160 through which extends the rear end of the rod 106, the latter being formed with a head 162, which is larger than the opening 160.

The above described device operates as follows:

With the parts in the position shown in the figures, the switch 110 is closed so as to supply current from the electric cord 141 to the motor 16, thus causing the latter to drive the fan so as to induce a flow of air through the inlet opening 20. This produces a partial vacuum within the housing 10, thus causing air to be introduced through the inlet opening conduit 46 to the interior of the dust bag 34, from whence it passes through the porous paper of the bag and the perforated body 32 to the fan inlet.

If it is desired to stop the motor the element 150 is pivoted in a clockwise direction, as viewed in Figs. 1 and 5. This causes the U-shaped member 142 to be pivoted in a similar direction, which in turn pivots the switch arm 128 in a clockwise direction so as to open the circuit through the switch. This pivoting of U-shaped member 142 may take place without effecting movement of the rod 106, inasmuch as the cross-member 146 merely moves away from the head 162 of the rod. In order to restart the motor, the element 150 is pivoted in the opposite direction so as to restore the parts to the positions shown particularly in Figs. 1 and 5.

As dirt-laden air is introduced into the dust bag 34, the dirt is separated from the air stream therein and collects on the inner surface of the porous bag portion 36, thus interfering with the flow of air and increasing the pressure drop through the bag. Inasmuch as the left-hand side of the diaphragm 56 is in communication

with the space between the bag and the fan inlet 20 through the conduits 60 and 66, while the right-hand side of the diaphragm is in communication with the space within the bag through the conduits 58 and 46, this increasing pressure difference causes the diaphragm to move to the left against the force of the loading spring 80. When the pressure drop has increased to a predetermined value, the diaphragm strikes the stem 78 of the valve 74 and further movement unseats the valve, thus establishing communication between the high vacuum chamber to the left of the diaphragm and the space within the cylindrical portion 68, which space is in communication through the tube 82 with the power diaphragm chamber, thus permitting atmospheric pressure to displace the diaphragm to the left, thus pivoting the latch 92 so as to disengage it from the keeper 98.

The weight of the cover 44, as well as the outward push of the rod 106 under the influence of spring 108, causes the cover to pivot to an open position. At the same time, the movement of the rod 106 to the left causes the head 162 thereof to engage the cross-member 146, thus pivoting the U-shaped member and the switch arm 128 so as to open the circuit through the switch.

The opening of the cleaner and stopping of the motor informs the operator that the dust bag should be replaced with a clean one. When this has been done and the front cover closed, it pushes the rod 106 to the right, but this does not actuate the switch, as the head 162 merely moves away from the cross member 146, and the switch will not be closed until it is actuated manually by means of the element 150.

While I have described one more or less specific embodiment of my invention, it is to be understood that this has been done for purposes of illustration only and that the scope of my invention is not to be limited thereby, but is to be determined from the appended claims.

What I claim is:

1. In an electric switching device, a switch case formed with a seat spaced inwardly from opposite sides of said case, said seat having an elongated slot therethrough, a toggle switch including a frame mounted in said seat and having an arm pivoted in said frame and extending downwardly through said slot, a U-shaped actuating member within said case having legs extending vertically on either side of said switch and seat, a cross member joining the lower ends of said legs and engaging the lower end of said pivoted arm, means for pivotally mounting the upper portions of said legs in opposite sides of said case, and a manually movable element connected to the upper ends of said legs above said switch and movable to pivot said U-shaped member and said switch arm.

2. In an electric switching device, a switch case formed with a seat spaced inwardly from opposite sides of said case, said seat having an elongated slot therethrough, a toggle switch including a frame mounted in said seat and having an arm pivoted in said frame and extending downwardly through said slot, a U-shaped actuating member within said case having legs extending vertically on either side of said switch and seat, a cross member joining the lower ends of said legs and engaging the lower end of said pivoted arm, a pin extending outwardly from the upper portion of each of said legs and pivotally received in recesses in opposite sides of said case for pivotally mounting said U-shaped member, and a manually movable element connected to the upper ends of said legs above said switch for maintaining said upper ends in spaced relationship and with said pins in said recesses, said element being movable to pivot said U-shaped member and said switch arm.

3. In an electric switching device, a switch case formed with a seat spaced inwardly from opposite sides of said case, said seat having an elongated slot therethrough, a toggle switch mounted in said seat and having a pivoted arm extending downwardly through said slot, a U-shaped

actuating member within said case having legs extending vertically on either side of said switch and seat, a cross member joining the lower ends of said legs and engaging the lower end of said pivoted arm, a semi-cylindrical pin extending outwardly from the upper portion of each of said legs and pivotally received in recesses in opposite sides of said case for pivotally mounting said U-shaped member, a manually movable element having a sliding connection with the upper ends of said legs above said switch for maintaining said upper ends in spaced relationship and with said pins in said recesses, and a semi-cylindrical pin extending outwardly from each side of said element and mating with the aforesaid pins in said recesses, said element being pivotal to pivot said U-shaped member and said switch arm.

4. In an electric switching device, a switch case formed with a seat spaced inwardly from opposite sides of said case, said seat having an elongated slot therethrough, a toggle switch mounted in said seat and having a pivoted arm extending downwardly through said slot, a U-shaped actuating member within said case having legs extending vertically on either side of said switch and seat, a cross member joining the lower ends of said legs and engaging the lower end of said pivoted arm, means for pivotally mounting the upper portions of said legs in opposite sides of said case, a manually movable element connected to the upper ends of said legs above said switch and movable to pivot said U-shaped member and said switch arm, and a switch actuating rod having a lost motion connection with said cross member and movable for pivoting said U-shaped member and said switch arm.

5. In an electric switching device, a one piece switch case of insulating material formed with a seat, a switch mounted in said seat, an elongated contact prong insertable lengthwise through an opening in a wall of said one piece case, means for securing said prong in fixed relation to said wall, an electric terminal on said switch, and means for securing the inner end of said prong to said terminal to establish an electrical connection therebetween and to hold said switch in said seat.

6. In an electric switching device, a switch case of insulating material formed with a seat, a switch mounted in said seat, a pair of contact prongs extending through spaced slots in a wall of said case, said wall having a

- bore intersecting said slots and each of said prongs having an aperture in alignment with said bore, a pin of insulating material disposed in said bore and extending through said apertures for securing said prongs in fixed relation to said wall, an electric terminal on said switch, and means for securing the inner end of one of said prongs to said terminal to establish an electrical connection therebetween and to hold said switch in said seat.
- 5 7. In an electric switching device, a switch case formed with a seat spaced inwardly from opposite sides of said case, said seat having an elongated slot therethrough, a toggle switch mounted in said seat and having a pivoted arm extending downwardly through said slot, a U-shaped actuating member within said case having legs extending vertically on either side of said switch and seat, a cross member joining the lower ends of said legs and engaging the lower end of said pivoted arm, a semi-cylindrical pin extending outwardly from the upper portion of each of said legs and pivotally received in open ended recesses in opposite sides of said case for pivotally mounting said U-shaped member, a manually movable element having a pair of sockets for slidably receiving the upper ends of said legs for maintaining said upper ends in spaced relationship and with said pins in said recesses, a semi-cylindrical pin extending outwardly from each side of said element and mating with the aforesaid pins in said recesses, said element being pivotal to pivot said U-shaped member and said switch arm, and means closing the open ends of said recesses for retaining said pins therein.
